By Cheever & Cox, Atty.

UNITED STATES PATENT OFFICE.

HERMAN H. WESTPHALN, OF HINSDALE, ILLINOIS, ASSIGNOR OF ONE-HALF TO ASA S. BACON, OF CHICAGO, ILLINOIS.

MAIL-BOX.

1,199,136.

Specification of Letters Patent.

Patented Sept. 26, 1916.

Application filed September 23, 1915. Serial No. 52,137.

To all whom it may concern:

Be it known that I, HERMAN H. WESTPHALN, a citizen of the United States, residing at Hinsdale, in the county of Du⁵ page and State of Illinois, have invented a certain new and useful Improvement in Mail-Boxes, of which the following is a specification.

My invention relates to mail boxes, more particularly for use in residences and in other places where mail is delivered by letter carrier.

The purpose of my invention is to obtain a receptacle into which the letter carrier may deliver mail from the outside of the residence, and the occupant of such residence or office may, from the inside, determine whether the box contains any mail, and if so, remove the contents without going to the outside of the building. In connection with this purpose it is my object to obtain a receptacle which, practically speaking is inaccessible from the outside of the building and which will hide the contents from a person outside of the building.

Another object of my invention is to provide means operable from the inside for holding an outgoing letter in position where it may be withdrawn by the letter carrier³⁰ and yet be held in a position where it will not interfere with the insertion of mail in case the carrier does not collect the mail.

I accomplish my objects by the construction illustrated in the accompanying drawings in which—

Figure 1 is a perspective of a receptacle embodying my invention. Fig. 2 is a central vertical section of the box showing it in position in a wall. Fig. 3 is a plan section taken just below the roof of the box.

Similar numerals refer to similar parts throughout the several views.

In the form selected to illustrate the invention, the box has a roof 1, a floor 2, side walls 3 and 4, and a front wall 5. In the design shown the receptacle is formed of sheet metal with flanges 6, 6 at the back against which are secured a back plate 7. This back plate supports a door consisting in the present instance of a frame 8 in which is mounted a plate 9 of glass. The parts 8, 9 may be considered in common parlance as a "glass door." When mounted in a building the face plate 7 will lie adjacent to the inside surface of the wall

and form a finishing frame to hide the rough edges where the wall is cut away to receive the receptacle.

At the outside or front the box is provided with a receiving spout 12 which is located at the upper end of the box, the outer end of the spout being provided with flanges 13 against which is fastened a face plate 14. The parts 13 and 14 are designed to lie adjacent to the exterior surface of the wall and form a finishing plate therefor. By preference the plate 14 is extended upward to form a card holder or name plate holder. This may be of any desired pattern.

Mounted within the box is a letter holder which consists in the present design of a spring wire 15 in the form of a bow, the forward end of the bow lying adjacent to the roof of the box and the ends extending obliquely downward and backward to the side walls 3, 4, where they are rigidly fastened in any suitable manner. The front of the bow is located preferably in or near the duct or spout 12 as illustrated, and presses upward.

In mounting the box it will be placed in the wall in the manner described, with the face plates 7 and 14 adjacent to the inner and outer wall surfaces respectively. The box will thus be accessible to the mail carrier from the outside and to the occupant from the inside. On account of the location and construction of the receiving spout, when the carrier has deposited a letter, it will drop to the bottom of the box and remain out of sight and out of reach of any body on the outside of the building. At the same time, however, the contents are at all times visible from the inside of the building and may be removed at any time at the convenience of the occupant. If the occupant wishes to send a letter (indicated by the lines 16 in Fig. 2), he inserts it through the door 8, 9 and over the top of the letter holder 15 which automatically engages the letter and holds it in contact with the under side of the roof 1. The occupant takes care that the end of the letter projects through the spout so that the outer end may be grasped by the carrier and be by him withdrawn from the box. As the holder keeps the letter adjacent to the roof, it leaves the duct free to receive letters, for it will be understood that the letter carrier does not always collect

mail and furthermore the mail box may be used by visitors or others for inserting visiting cards, etc. Consequently in my construction the outgoing letters do not obstruct the receiving opening in any way and the shape of the letter holder is such as to permit letters to be freely introduced from the outside.

It will be understood, of course that the thickness of the box from front to rear may be varied to suit occasions. For example, a box of my general design may be employed in an office building where the partitions are thinner.

What I claim as new and desire to secure by Letters Patent, is:—

1. A mail box having a receiving slot in the front near the top and a letter holder near the slot for holding a letter in a position where it will project out through the slot at one edge of the slot whereby it may be grasped by the mail collector and yet not obstruct the slot to any appreciable extent.

2. A mail box having a receiving slot in the front near the top and an opening in the back and a resilient letter holder near the slot pressing toward the top of the box for yieldingly holding a letter in a position where it will extend out through the slot at the upper edge thereof, said letter holder being open at the back for permitting said letter to be inserted from the back opening

of the box and move in the same general direction that the letter will take in being withdrawn from said slot by the mail collector.

3. A mail box having openings on two different sides, one opening being large for the ready removal of mail and the other one small and located near the top of the box to prevent removal of the contents supported upon the floor of the box, and a letter holder adjacent to the smaller opening, said holder being adapted to hold a letter approximately parallel to the position a letter will normally assume in entering the box through the smaller opening.

4. A mail box having a receiving slot at one side, an opening at the opposite side for the removal of mail, and a spring wire bow fastened at its ends to the sides of the box and extending from the ends toward the central upper part of the box for pressing a letter against the roof of the box while said letter is partially within the box and in part projects through said slot, the bow being opposite to and inside of said slot and the ends being somewhat lower than the roof of the box to thereby permit the owner to slip an outgoing letter into the holder from the back of the box.

In witness whereof, I have hereunto subscribed my name.

HERMAN H. WESTPHALN.
